EMILE MARIUS LAURENT, OF ST.-MANDE, FRANCE

FLYING APPARATUS

Application filed July 14, 1928, Serial No. 292,685, and in France August 4, 1927.

This invention relates to an absolutely novel flying apparatus which is characterized by a special arrangement which will be hereinafter described.

This apparatus, the characteristic arrangements of which remain in all cases the same, may be realized under the most various forms of construction, one of said constructions being shown, by way of example, in

10 the accompanying drawing:

Fig. 1 is a rear-elevation of the flying apparatus.

Fig. 2 is a side-elevation of Fig. 1.

Fig. 3 is a cross-section on larger scale of 15 one of the turbines.

Fig. 4 shows in side-elevation a modified form of construction of the flying apparatus.

Fig. 5 is a top plan view of Fig. 3.

Fig. 6 is a cross section showing the turbines on larger scale.

Fig. 7 shows a modification.

In order to make the drawing more clear certain elements or axles are somewhat displaced from their real position. The apparatus designed to be carried on the back, shown in the first form of construction in Figs. 1, 2 and 3, comprises a cuirass *a* of moulded aluminium which covers the back from the hips to the shoulders and is lined 25 with felt and fitted with straps so that it

30 can be fixed on the body. This cuirass is extended at the lower end by a frame *b* to which two stirrups *b'* are fixed on which the feet have to be placed. The upper portion of the cuirass comprises a head-protector *a'* and two reinforced shoulder-pieces *a''*, *a'''* which project laterally and are designed to permit the arrangement of a ball joint. At the end of each shoulder-piece a movable 35 supporting plane or wing *c* is arranged which is connected to the shoulder-piece by means of a ball-joint *c'* and can adopt, under the action of the arms (the bands being inserted into the handles *d*), any inclined position 40 in the direction of movement from the horizontal to the vertical.

On the sides of the cuirass *a* and of the frame frames *f* of steel tubes are mounted over which canvas is stretched to form the 45 supporting planes.

At about $\frac{1}{3}$ of the height of the cuirass *a* and on the rear of the same a motor *g* is mounted which consists of an absolutely oval-case and of two V-shaped cylinders, said case carrying a crank-shaft *h* projecting 55 over each side and carrying at each end a pinion. These two pinions drive a transverse shaft *i* through the intermediary of two gear-wheels keyed on this shaft.

The transverse shaft *i* carries on each end 60 a turbine *j* and at its centre in the case a spur-wheel which, by convenient teeth, rotates the shaft *k* of the propeller *l*, arranged above the cuirass *a*. This propeller-shaft *k*, conveniently supported by means of ball 65 bearings and supports, has a hollow upper portion with which engages a second shaft carrying a ram and comprising a clutch controlled by a cable to operate from below the right movable wing.

70 A housing *m* serves for accommodating several accessory elements.

Each turbine is constituted by several extensible blades *2*, for example four, which are mounted on a hub rigid with the shaft *i*. 75 This hub is eccentric with regard to a guide or circular rail *3* on which bear, under the action of springs having the tendency to develop said blades, the rollers *4* which are carried by the same.

80 Fig. 3, in which the arrow-line *5* indicates the direction of movement and the arrow-line *6* the relative direction of the streamlines with regard to the turbine, shows that the repulsing is complete only at the desired 85 moment without the production of a contrary reaction, owing to this fact.

The apparatus of the second form of construction, Figs. 4, 5 and 6, comprises the same essential elements and is constructed 90 according to the same characteristics with a somewhat stronger motor.

95 For the cuirass is however substituted an oval very comfortable fuselage and the apparatus, instead of being carried on the back, is mounted on an apparatus *o* for landing.

The stability is ensured by two stationary supporting planes *p*, *p*, fitted with two double turbines *q*, *q*, and of two small movable 100

supporting planes or wings r, r designed for permitting alterations of inclination.

The elements of the motor s accessible by hand are covered by a plane t slightly smaller than the whole supporting planes p, p . Under this plane t the pilot's seat and the driving elements are arranged.

The frame n , which forms the extension of the fuselage, carries at its rear-part a vertical rudder v and a horizontal rudder x .

For the special turbines described above, propellers with vertical axles as shown in Fig. 7 might be substituted.

I claim:—

15. 1. A flying apparatus, comprising in combination a cuirass to be fixed on the body to cover the back and the head, a propeller, two movable lateral planes the angle of inclination of which may be altered at will, 20 means for operating by hand said lateral planes, two lateral stationary supporting planes, two supporting turbines with eccentric extensible blades, and a motor with oval case arranged on said cuirass and driving said turbines and said propeller.

2. A flying apparatus comprising in combination a cuirass to be fixed on the body to cover the back and the head, a propeller, two movable lateral planes the angle of inclination of which may be altered at will, means 30 for operating by hand said lateral planes, two lateral stationary supporting planes, two supporting propellers, and a motor with oval case mounted on said cuirass and driving said propellers.

In testimony whereof I affix my signature.
EMILE MARIUS LAURENT.
